C. H. WILLIAMS.

FOURTH POINT SUPPORT FOR BRAKE BEAMS.
APPLICATION FILED FEB. 27, 1918.

1,304,135.

Patented May 20, 1919.

Inventor

Charles Haines Williams

By *J. K. Gammie, Atty.*

UNITED STATES PATENT OFFICE.

CHARLES HAINES WILLIAMS, OF CHICAGO, ILLINOIS, ASSIGNOR TO CHICAGO RAILWAY EQUIPMENT COMPANY, OF CHICAGO, ILLINOIS, A CORPORATION OF ILLINOIS.

FOURTH-POINT SUPPORT FOR BRAKE-BEAMS.

1,304,135.

Specification of Letters Patent. Patented May 20, 1919.

Application filed February 27, 1918. Serial No. 219,433.

To all whom it may concern:

Be it known that I, CHARLES HAINES WILLIAMS, a citizen of the United States, residing in the city of Chicago, county of Cook, and State of Illinois, have invented a certain new and useful Improvement in Fourth-Point Supports for Brake-Beams, of which the following is a full, clear, and exact description, such as will enable others skilled 10 in the art to which it appertains to make and use the same, reference being had to the accompanying drawings, forming part of this specification.

Figure 1 is a diagrammatical plan view 15 of my improved fourth point support for brake beams.

Fig. 2 is a sectional view on line 2—2 of Fig. 1.

Fig. 3 is a plan view of a modified form 20 shown in Fig. 4.

Fig. 5 is another modified form.

Fig. 6 is a plan view of a modified form shown in Fig. 7.

Fig. 8 is a plan view of another modified 25 form shown in cross section in Fig. 9.

This invention relates to a new and useful improvement in fourth point supports for 30 brake beams, the object being to strengthen the beam at or near the brake heads by providing an additional connection between the compression and tension member at this point, which not only gives to the beam a better balance, but tends to overcome the tendency of the beam to be tossed up and 35 back in the release of the brakes.

Another object is to simplify the construction whereby the parts may be cheaply manufactured and easily applied.

In the drawings, 1 represents the compression member of a brake beam, 2 the tension member, 3 the strut, and 4 the brake head. 5 is the spring plank or other part of the truck to which the track supports 6 are connected. 7 indicates a member which, 40 as shown in Figs. 2 and 3, is bolted or otherwise secured to the compression member 1 and is fastened to the tension member 2, said brace member being provided with a rubbing shoe 8 at its inner end.

In Fig. 4, I have shown this rubbing shoe 50 8^a as being formed with a tongue pressed out of the brace member, whereas in Fig. 5, it is formed by bending the material upon itself as at 8^b to form a wearing shoe.

In Figs. 6 and 7, a tongue is cut in the 55 brace member to form a clamping element 9, and the end of said brace member is folded upon itself as at 8^c to form a wearing surface.

In Figs. 8 and 9, two tongues 10 are 60 formed to embrace the tension rod and the end of the brace member is bent as at 8^d to form the supporting element.

It will be readily understood, of course, that still other modifications and adaptations of my improved fourth point support for brake beams may be made without departing from the scope and spirit of what I claim to be my invention.

What I claim is:

1. A fourth point support for brake beams comprising a trussed brake beam, in combination with fourth point supporting tracks and bracing members connected to the compression and tension members of the beam, 75 said bracing members having integral supporting elements carried thereby for riding upon said tracks.

2. A fourth point support for brake beams comprising a bracing element connected to 80 the tension and compression members and carrying a supporting member located beyond the tension member for coöperating with the fourth point supports.

3. A support for brake beams comprising 85 a bracing element connected to the tension and compression members and extending beyond the former, said bracing element carrying at its extremity a supporting member for coöperating with the brake beam 90 support.

In testimony whereof I hereunto affix my signature this 9th day of February, 1918.

CHARLES HAINES WILLIAMS.
